VENDING MACHINE

Axel N. Krohn, Chicago, Ill.

Application December 10, 1934, Serial No. 756,845

5 Claims. (Cl. 194—57)

This invention relates to a vending machine, and particularly to such a machine adapted to vend bars of candy, chewing gum or similar articles, the same being constructed and arranged 5 to be operated by a coin.

In vending machines for vending such articles as above noted it has usually been necessary to have the candy or other article placed in a box or carton of rectangular outline.

10 It is an object of this invention to provide a vending machine so constructed and arranged that candy bars or other articles can be placed therein and be successfully discharged upon the deposit of a coin without being disposed in special 15 cartons or boxes.

It is a further object of the invention to provide 20 a vending machine comprising a vertically extending casing with an endless member therein having open-sided carriers with their open sides moving adjacent the sides of said casing to retain articles 25 therein.

It is a further object of the invention to have 30 such a machine as set forth in the preceding paragraph so arranged that the lowermost carrier 25 will discharge its article which will be guided by a plate through an opening in the front of said casing.

It is still another object of the invention to provide 35 such a vending machine as above set forth in which said endless carrier is intermittently moved by a rotating shaft geared to a second shaft, said second shaft carrying a member adapted to be rotated by engagement of the deposited coin.

40 These and other objects and advantages of the invention will be fully set forth in the following description made in connection with the accompanying drawing, in which like reference characters refer to similar parts throughout the several views and in which:—

Fig. 1 is a vertical section taken on line 1—1 of Fig. 2;

Fig. 2 is a horizontal section taken on line 2—2 of Fig. 1;

45 Fig. 3 is a vertical section taken on line 3—3 of Fig. 2;

Fig. 4 is a partial view similar to Fig. 3 showing the parts in different positions;

Fig. 5 is a horizontal section taken on line 5—5 of Fig. 3; and

Fig. 6 is a vertical section taken on line 6—6 of Fig. 5, said sections being taken as indicated by the arrows.

Referring to the drawing, a vending machine 55 is shown comprising a casing 10, said casing being

of upright or vertically extending form having a rear wall 10a, a front wall 10b, side walls 10c and a bottom 10d. Front wall 10b curves rearwardly at its upper portion and extends to rear wall 10a in a substantially horizontal plane to form the top wall 10e. The lower portion of front wall 10b is bent inwardly as shown in Fig. 1 to provide an opening 10f in the front of casing 10 at the bottom thereof. A plate 9 has its upper end disposed closely against the rear wall 10a some distance above bottom 10d, the same curving downwardly and rearwardly from said upper end and extending downwardly to the rear side of opening 10f. The front and rear walls 10a and 10b have their vertical edges turned inwardly as shown at 10g. 15 The side wall 10c is reversely bent or folded and has flanges 10h projecting inwardly adapted to fit within the bent portions or flanges 10g. Side wall 10c is thus made removable but is adapted to be locked in position to casing 10 by means not shown. Said casing 10 is preferably made of sheet metal and a plate 11 is shown as disposed along the inner side of the front wall 10b and while this plate may be of different materials it is illustrated as being made of wood. Another 20 plate or strip 12 extends along and is secured to the inner side of one side wall 10c. A U-shaped bracket 13 is secured to the rear wall 10a by the nutted bolt 14 and has arms projecting toward the front wall 10b and extending downwardly and 25 secured to bottom 10d by bolts 13a. A shaft 15 extends through and is journaled in one arm of bracket 13 and in a bearing 16 carried by the strip 12. A small gear or pinion 17 is secured to shaft 15 in any suitable manner as by pin 18, the 30 hub of said gear engaging the side of one arm of bracket 13. Shaft 15 has secured thereto at spaced points sprocket wheels 19. Brackets 20 are secured at their ends respectively to strip 12 by the bolts 21 and extend upwardly and down- 35 wardly respectively, the lower bracket 20 having a bearing 20a at its end against which the hub of one sprocket 19 engages, shaft 15 passing through and being journaled in said bearing. Endless chains 22 pass around the lower sides of 40 sprockets 19 and at their upper ends pass around disks 23 secured in spaced relation to a shaft 24 journaled in bearings carried by strip 12 and in a bearing carried at the upper end of upper bracket 20. A plurality of article carriers 25 are pro- 45 vided having open sides and while the shape of these carriers might be varied, in the embodiment of the invention illustrated they are shown as formed of sheet metal bent into trough shape and being rectangular in vertical cross section. 55

Said carriers have secured thereto at spaced points U-shaped clips 26 having their sides apertured to receive small rods 27 which extend between the chains 22 and have their ends bent at 5 a right angle at the outer sides of clips 26. It will be noted that carriers 25 have their open sides moving adjacent the rear wall 10a and front plate 11 so that articles carried therein will be retained therein by said wall and plate.

10 A second shaft 28 extends between and is journaled in the arms of bracket 13 forwardly of shaft 15, said second shaft being parallel to shaft 15. A gear 29 meshing with and of much greater diameter than gear 17 is secured to shaft 28 in 15 any suitable manner as by pin 30 and a toothed wheel 31 is also secured to shaft 28 in any suitable manner as by pin 32. Another wheel or disk 33 is secured to shaft 28 in any suitable manner as by pin 34. A bracket 35 is secured to 20 front wall 10b and a lever 36 is pivoted to said bracket by pivot member 37. Lever 36 extends over disk 33 and said disk has in its periphery a plurality of circumferentially spaced notches 33a. Lever 36 has a projection 36a adapted to 25 enter one of the notches 33a and said lever is normally urged to position with said projection 36a engaging in a notch by a spring 38 secured to the rear end of lever 36 and to a guide member 39 to be later described. Guide member 39 comprises 30 vertically spaced plates 39a extending beneath shaft 28 and parts carried thereby, said plates forming a passageway for a coin 40 which may be deposited on the lower of said plates through an opening 39b in the top plate in front 35 of the front wall 10b. A plunger 41 is also slideable in the passageway between plates 39a, the same having an opening or slot 41a in its rear end of sufficient width to receive coin 40, the rear end of said plunger having its end upturned as 40 shown at 41b in Fig. 6. The outer end of plunger 41 is downturned as shown at 41c to form a handle. Plate or guide member 39 is supported on an angle bracket 42 secured to its under side and to the front wall 10b. The lever 36 has its 45 free end extending downwardly into a narrow slot 39c formed in plates 39a some distance inwardly of front wall 10b and the lower side of the toothed wheel 31 is also disposed in said slot, the teeth thereof being so disposed as to be engaged at their edges by coin 40 when moved in 50 said guideway.

In operation, the side wall 10c will be removed and the carriers 25 will be loaded with the articles to be dispensed, such as candy bars. These 55 bars as stated need not be placed in boxes but may be placed in the carriers 25 merely wrapped as usual in paper. Articles can be placed in all of the carriers 25 except the lowermost one. Side 10c will now be replaced and locked in position.

60 Lever 36 is normally in the position shown in Fig. 3 and slide or plunger 41 is normally in the position shown in Fig. 3. Should a person desire to secure a candy bar he will place his coin, such as a nickel, in the opening 39b and in opening 65 41a and said coin will rest on lower plate 39a. The person now pushes in plunger 31 and the coin is engaged by the end of slot 41a and moved inwardly. The coin first presses on lever 36, moving its lower end inwardly and raising its 70 upper end against the tension of spring 38 so that projection 36a is withdrawn from one of the notches 33a. The coin passes under the lower end of lever 36, said end riding over said coin and again moving into slot 39c in the rear of 75 said coin. Coin 40 then engages a tooth of wheel

31 and said wheel is rotated through a partial revolution rotating shaft 28 and through the gears 29 and 17 rotating shaft 15 and sprockets 19 and moving the chains 22. A carrier 25 is thus moved into discharging position at the bottom of said chains and the article therein is discharged onto plate 9 and slides down thereon forwardly through opening 10f. When the coin has been pushed in as far as it can be by plunger 41, projection 36a again engages in one of the 10 notches 33a and the machine is again in normal position. It will be understood that wheel 31 and disk 33 were rotated sufficiently by the coin to bring the notch engaged by projection 36a out of alignment therewith before the coin passed 15 out of engagement with the lower end of lever 36. When the next coin is placed in the machine and plunger 41 operated, another article will be dispensed and the previous coin will be pushed beyond the end of guideway 39 and will 20 drop into the bottom of the casing which forms a coin box. It will be seen as shown in Fig. 1 that the articles will be discharged from the carriers 25 and will slide downwardly and outwardly on plate 9 through opening 10f. It will 25 be also understood that the lever 36 with its projection 36a acts as a stop pawl for wheel 31, preventing backward movement of the latter.

From the above description it is seen that applicant has provided a very simple and yet a very 30 efficient vending machine. The machine can be easily loaded with the articles to be dispensed and the articles will successively be dispensed upon the deposit of the coins. The device has been amply demonstrated in actual practice and 35 found to be very successful and efficient.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:—

1. A device of the class described having in combination, a member adapted to be intermittently moved including a shaft, a second shaft parallel thereto, gearing connecting said shafts, a wheel having projecting teeth at its periphery secured to said second shaft rotating in a vertical plane, a plate at the lower side of said wheel disposed in a horizontal plane and having a slot therein into which the lower teeth of said wheel extend, said plate being constructed and arranged to support a coin, a guideway for said coin above said plate, a plunger movable in said guideway toward said wheel, a second wheel having circumferentially spaced notches therein secured to said second shaft, a lever pivoted adjacent said 60 wheels having a projection adapted to enter one of said notches and having a portion extending into said guideway in the path of said coin, a spring urging said lever to position with said projection engaging in one of said notches so 65 that a coin moved by said plunger will swing said lever and remove said projection from said notch and said coin will then move against a tooth of said first mentioned wheel and rotate the same until said projection engages another of said 70 notches.

2. A device of the class described having in combination, a shaft adapted to be intermittently rotated, a plate-like wheel secured to said shaft having projecting teeth, said wheel being 75

disposed in a vertical plane, a coin-supporting plate and guideway at the lower portion of said wheel disposed in a horizontal plane and having a vertical slot therein into which the lower teeth 5 of said wheel project, a second wheel of smaller diameter than said first mentioned wheel secured to said shaft having circumferentially spaced notches in its periphery, a member pivoted at one side of said second wheel extending 10 thereover and having a projection adapted to enter one of said notches at the upper portion of said second wheel, said member having a portion below its pivot extending into said slot, a plunger movable in said guideway for moving 15 a coin therein and on said plate, said coin being adapted to engage said member and swing the same to remove said projection from its notch, said coin then engaging one of the teeth of said first mentioned wheel and rotating the same until 20 said projection enters another notch on said second wheel and resilient means for moving said member to position to move said projection into one of said notches.

3. A device of the class described having in combination, a shaft adapted to be intermittently rotated, a plate-like wheel disposed in a vertical plane secured to said shaft and having teeth projecting at its periphery, a support and guideway for a coin at the lower portion of said wheel 25 including a plate disposed in a horizontal plane, the same having a slot therethrough extending parallel to the plane of said wheel into which the lower teeth of said wheel project, a member secured to said shaft having stop means thereon, a second member pivoted at one side of said member having a downwardly projecting portion 30 extending into said slot, said second member extending over said first mentioned member and having means to engage said stop means to prevent rotation of said wheel, resilient means urging said second member to position to move said means into engagement, a plunger movable in said guideway to move a coin therein so that its

edge engages the lower portion of said second member and swings the same to disengage said means and permit rotation of said wheel, said coin then engaging one of the teeth of said first mentioned wheel and rotating the same until 5 said means again engage to stop rotation of said wheel.

4. A device of the class described having in combination, a member adapted to be intermittently moved including a shaft, a second shaft 10 parallel thereto, gearing connecting said shafts, a wheel having projecting teeth at its periphery secured to said second shaft rotating in a vertical plane, a plate at the lower side of said wheel disposed in a horizontal plane and having a slot 15 therein into which the lower teeth of said wheel extend, said plate being constructed and arranged to support a coin, a guideway for said coin above said plate, a plunger movable in said guideway toward said wheel, whereby a coin 20 moved by said plunger will be positioned in a plane perpendicular to the plane of said wheel and will engage one of said teeth and rotate said wheel and means holding said wheel against rotation but engaged by said coin and moved to 25 release said wheel.

5. A device of the class described having in combination, a member adapted to be intermittently moved including a shaft, a second shaft 30 adjacent said shaft, means connecting said shafts for simultaneous rotation, a wheel having projecting teeth at its periphery secured to said second shaft and rotating in a vertical plane, a member having a substantially horizontal coin-supporting surface below which surface the lower 35 teeth of said wheel project, means for moving a coin on said surface to engage a tooth on the lower side of said wheel for rotating said wheel and means holding said wheel against rotation but engaged by said coin and moved to 40 release said wheel for rotation by said coin.
